COLLAR DISPLAY HOLDER

Morton Wald, New York, and Julius Brooks, Brooklyn, N. Y., and John Leaman, Duluth, Minn.; said Brooks assignor to Ira Silverman, New York, N. Y.

Application March 22, 1947, Serial No. 736,528

2 Claims. (Cl. 223—83)

1

This invention relates to a collar display holder for use in displaying shirts with collars thereon.

It is an object of the present invention to provide a collar display holder with an opening in the top whereby access can be had to the front portion of the collar holder to permit the easy fixing or fastening of the top button of the shirt.

It is another object of the present invention to provide on the holder an easy handle which will be attractively disposed across the top of the holder and by which the collar holder can be extracted from the shirt.

It is still another object of the present invention to provide means on the bottom edge of the holder which will extend laterally into the sides of the shirt whereby to better retain the collar of the shirt in its attachment with the shirt and to prevent its displacement therefrom.

According to the invention, there has been provided a collar holder with an opening in the top and a strip extending across the top from one side to the other either in a diagonal or straight manner to serve as the attractive display for advertising matter and also as a handle by which the holder can be extracted from the shirt and wherein between the handle, there are openings through which access can be had to facilitate the fixing of the top button of the shirt under the holder.

According to a modified form of the invention, there are provided projections which extend laterally from the bottom edges of the holder so as to provide a better attachment of the holder with the shirt.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view looking upon the front of a collar holder wherein there is a portion extending diagonally across the top and wherein there are openings by which access can be had to the interior of the holder to fasten the button.

Fig. 2 is a front elevational view of the form of the invention shown in Fig. 1.

Fig. 3 is a perspective view of a modified form of the invention in which there are a transversely extending handle portion and an inwardly extending flange whereby to stiffen the top part of the holder.

2

Fig. 4 shows either one of these holders shown in Fig. 1 and 3 inserted in a shirt to display the collar thereof.

Fig. 5 is a transverse cross sectional view taken on line 5—5 of Fig. 3, looking in the direction of the arrows thereof.

Fig. 6 is a modified form of the invention including projections adapted to extend laterally into the shirt whereby to better fix the holder to the shirt.

Fig. 7 is a fragmentary cross sectional view taken on line 7—7 of Fig. 6, looking in the direction of the arrows thereof.

Referring now particularly to Figs. 1 and 2, 15 16 represents a holder having a depending side wall 11 on the front of which is a notch 12 adapted to fit over the front button of a neck band type shirt. In the rear of the wall is a second notch 13 adapted to receive a collar button if the shirt being displayed is of the neck band type. Across the top of the side wall and disposed in a diagonal fashion is a handle portion 15 on which advertising matter can be displayed. By the use of the handle 15, the holder can be 20 inserted and extracted from the shirt collar.

Referring now particularly to the form of the invention shown in Fig. 3, it will be noted that there is provided a handle portion 16 which extends straight across the holder and wherein 30 there are provided openings 17 and 18 at the opposite sides of the handle 16 so that the hand can be inserted into the holder for fixing the top button of the shirt of the neck band type which will lie within a notch 19 in the front of a depending wall 21 of the holder. In order to give more rigidity to the holder, there is provided an inwardly extending flange 22 which will not interfere with the openings 17 and 18 but at the same time will provide a more rigid holder piece. 35 40 Both of these holders as with the old style holders are formed of celluloid and have a glossy finish thereon. Printed matter can be disposed thereon with gold or light colored letters.

Referring particularly to Fig. 4, it will be noted 45 that the holder is readily inserted within the collar of a shirt and will keep the same retained in an upright manner while the shirt is being displayed in a store window. The shirt is indicated at 23 and is suitably folded so as to 50 properly display the shirt and at the same time to minimize the space which is consumed by it.

Referring now particularly to Figs. 6 and 7, there is shown a still further form of the invention wherein the radially inwardly extending flange 22 is utilized with a diagonally extending

handle portion 15. An opening 19 is provided to permit access to the top button of the shirt. On the depending wall, there are provided a plurality of laterally extending projections 24 which will extend into the shirt material and better retain the holder therewithin. These projections are in the form of a tongue with rounded ends to permit their easy insertion in the shirt material. These projections 24 do not in any way interfere with the opening 19 through which access is gained to the shirt button.

While we have illustrated and described the preferred embodiments of our invention, it is to be understood that we do not limit ourselves to the precise constructions herein disclosed and the right is reserved to all changes and modifications coming within the scope of the invention as defined in the appended claims.

Having thus described our invention, what we claim as new and desire to secure by United States Letters Patent is:

1. In a collar holder for insertion into the collar of a freshly laundered and folded man's shirt and having a top wall substantially flush with the top edges of the collar and a depending skirt wall of a height corresponding substantially with the height of the collar, projections extending radially outward from the bottom edges of the skirt wall for insertion between the layers of material of the folded shirt adjacent the collar for retaining the holder in position in the collar, said projections having their free ends rounded to facilitate their insertion between the layers of material, the top wall being formed with spaced opposed semi-circular openings dividing off a handle by which a grip can be had on the holder for pulling it out of the collar against the holding action of said projections.

2. In a collar holder for insertion into the collar of a freshly laundered and folded man's shirt and having a top wall substantially flush with the top edges of the collar and a depending skirt wall of a height corresponding substantially with the height of the collar, projections extending radially outward from the bottom edges of the skirt wall for insertion between the layers of material of the folded shirt adjacent the collar for retaining the holder in position in the collar, said projections having their free ends rounded to facilitate their insertion between the layers of material, the top wall being formed with spaced opposed semi-circular openings dividing off a handle by which a grip can be had on the holder for pulling it out of the collar against the holding action of said projections, said projections being located only at the front of the skirt wall for insertion beneath the collar and the front material of the shirt.

MORTON WALD,
JULIUS BROOKS,
JOHN LEAMAN.
